UNITED STATES PATENT OFFICE.

PAUL H. BRINK AND JAMES B. AYERS, OF NEW YORK, N. Y.

BOTTLE-CAP.

SPECIFICATION forming part of Letters Patent No. 364,334, dated June 7, 1887.

Application filed March 9, 1887. Serial No. 230,210. (No model.)

To all whom it may concern:

Be it known that we, PAUL H. BRINK, a subject of the Emperor of Germany, and JAMES B. AYERS, a citizen of the United States, both residents of New York city, in the county and State of New York, have invented a new and useful Improvement in Bottle-Caps, of which the following is a specification.

Our invention has for its object to furnish a bottle-cap that shall be air-tight, easily opened to allow the contents of the bottle to be poured out, and quickly and securely shut or fastened when the desired quantity has been withdrawn, that will be adjustable, so as to fit the neck of any ordinary bottle, and can be quickly applied or removed from the same, and that will dispense with the use of corks or other stoppers for all non-effervescent liquids, either during their shipment or actual use. The said bottle-cap is ornamental in appearance and efficient in use, and can be cheaply manufactured.

Our invention consists of a bottle-cap adapted to cover the mouth of a bottle, and extending for a short distance down the outside of same, said cap consisting of a metallic shell divided centrally into two equal parts, said equal parts being joined together by a spring-hinge. Said cap is also provided with a rubber lining and a spring-catch, for purposes to be herein-after described; also, a standard to support said cap, made integral with an open ring that clasps the neck of bottle, the ring terminating in lugs and shoulders to limit the opening of cap, all as hereinafter described.

Figure 1 represents a perspective view of our improved bottle-cap as it appears closed and in position on the neck of a bottle. Fig. 2 is a plan view of cap in an open position attached to a bottle. Fig. 3 is a sectional plan view on line $y-y$ of Fig. 4, showing cap closed and fastened in that position. Fig. 4 is a vertical section taken on line $x-x$ of Fig. 3, showing cap closed. Fig. 5 is a detail view. Fig. 6 is a view of a modified form of our cap, parts being in section.

Similar letters of reference indicate corresponding parts in all the figures.

A represents the top part or neck of a bottle. B represents an open ring, terminating at either end in projecting lugs $b-b$. Said lugs

$b-b$ are provided with screw-threaded holes adapted to receive a screw, c. This screw c is of some length to admit of adjusting the ring B to the different-sized necks of various bottles. By loosening or tightening said screw c the ring B will be enlarged or contracted, and thus made to tightly clasp the neck of any bottle.

A standard, C, made integral with the ring B, rises upwardly from said ring, and has its apex formed into a pintle, D, to receive the knuckles d, attached to cap E to form a hinge, H.

Confined between the upper and lower pairs of knuckles d and wound around the pintle D is a coiled spring, F. The upper and lower extremities of said spring are extended sideways in opposing directions, as shown at f' and f'' and as represented in drawings. The extension f' will be fastened to the inner side of one section of cap E, and extension f'' to the inner surface of the opposite section of cap E. Said spring F at all times has a tendency to swing each of the cap-sections outwardly and away from each other, both sections of cap E swinging on pintle D, and to uncover the mouth of bottle, as represented in Fig. 2.

Lugs g g are formed on upper portion of and integral with the standard C, and, as shown clearly in Figs. 1 and 5 and in dotted lines in Fig. 4, receive the two lower knuckles of hinge H between them, and control the outward throw of both sections of cap E by the respective halves of cap E being brought up against said lugs g g, as shown in Fig. 2.

The cap E is a metallic shell covering the mouth of bottle and extending down upon the outside of same for half an inch or thereabout, and consists of two equal sections, E' and E''. These sections E' and E'' are united, as before described, by a spring-hinge, H, and a spring-catch, I, is arranged diametrically opposite, as shown best in Fig. 3.

The entire inner surface of both sections of cap E is covered with rubber, E³, to exclude air, dust, &c., and prevent evaporation or leakage of contents of bottle when cap is closed.

The catch I consists of a flat spring, i, riveted to one half-section, E'', of cap E, and provided with an outwardly-projecting pin, f. This pin is beveled or rounded off on the side approaching the opposite section, E', of cap E,

so as to be acted upon by opposite section, E', when the two sections E' and E² of cap E are brought together and pass inside the shell of section E', depressing the spring i until pin f 5 meets hole in keeper h, when the spring i will force the pin f to enter hole in keeper h and lock both sections firmly together, as shown best in Fig. 3. Spring i is also provided with a button, h², the stem of which passes loosely 10 through a hole formed in the meeting edges of the two sections E' and E², and then attached to spring i. By pushing button h² inwardly the spring i will be forced back sufficiently to disengage the pin f, attached to spring i, from keeper h, and the two sections of cap E will be instantly thrown outwardly into position 15 shown in Fig. 2 by the action of the coiled spring-hinge H, uniting said sections.

To accommodate the necessary movement of 20 spring-catch I and to receive the same, a swell, N, is formed on each of the front meeting edges of the bottle cap-sections E' and E² of such dimensions as to insure the easy working of said catch I.

25 The operation is as follows: When cap is closed and it is desired to use the liquid in bottle, grasp the neck of bottle and press with thumb on button h². This releases the front edges of the cap-sections E' and E², and the 30 action of the spring-hinge H upon them will cause said sections to swing outwardly and in opposite directions on pintle D until the movement of each of said sections is arrested by striking the lugs g g, as shown in Fig. 2, thus 35 fully exposing the mouth of bottle. The spring F will retain said sections in this opened position until the necessary quantity of liquid has been poured out of bottle, when, by placing the hand over both sections of cap E and 40 pressing them toward each other, the pin f on spring i will be engaged by keeper h and hold cap securely closed as soon as the meeting edges of the cap-sections are closely brought together.

45 The name of the contents of bottle may be suitably engraved upon outside face of bottle-cap E.

The ring B, with its lugs b b, standard C, with its lugs g g, and the blank to form the 50 pintle D will be struck up out of one piece of thin metal and then bent to desired shape.

The sections E' and E² of cap E will be thin metal castings with the knuckles d formed upon them, thus reducing their cost of manufacture to a minimum.

55 In case of breakage the parts can be easily removed and replaced, the head of pintle D being but slightly swaged down on a washer placed on top knuckle of hinge H.

60 From above description it will be seen that when the cap is closed it will be impossible for air to enter bottle, or the contained liquid to evaporate or be spilled; also, that the device protects the contents from the entrance of dust or insects.

65 When it is desirable to use our bottle-cap

on bottles that vary considerably in the distance from the mouth of bottle to the commencement of neck, we make the standard C and open ring B independent of each other, 70 and provide a block, K, fastened to ring B, with a slot in it to receive and hold the standard C and allow the standard C to be freely moved up or down to adjust cap E to mouth of bottle, and to be held in any such position 75 by tightening the screw L.

Having thus described our invention, we claim as new and desire to secure by Letters Patent—

1. The combination, with two bottle-cap 80 sections formed with hinge-knuckles, of a pintle by which the said sections are connected, a spring carried by the pintle and arranged to bear against the cap-sections, and means, substantially as described, for locking the sections together in a closed position, all as hereinbefore set forth.

2. The combination, with a sectional bottle-cap, of a supporting-standard to which the sections of the cap are connected and a spring- 90 catch carried by one of the sections and arranged to engage with the other section, substantially as described.

3. The combination, with a bottle-cap made in sections, of a cap-supporting standard, an 95 opening spring, and a spring-catch, said catch being carried by one of the cap sections and arranged to engage with the other, substantially as described.

4. The combination, with two cap-sections 100 having hinge-knuckles, of a standard formed with a pintle with which said knuckles engage, a spring coiled about the pintle and engaging with the cap sections, a means for connecting the standard to the bottle, and a spring- 105 catch carried by one of the cap sections, substantially as shown and described.

5. The combination, with two cap-sections having hinge-knuckles, of a standard formed with a pintle, which said knuckles engage, 110 and with side stops, a spring coiled about the pintle and engaging with the cap-sections, a means for connecting the standard to the bottle, and a spring-catch carried by one of the cap-sections and arranged to engage with the 115 other, substantially as described.

6. A bottle-cap support consisting, essentially, of a standard, a pintle, stops at either side of pintle, and an open ring having lugs formed on its approaching ends, all said parts 120 being integral, substantially as shown and described.

In testimony that we claim the foregoing as our invention we have signed our names, in presence of two witnesses, this 5th day of 125 March, 1887.

PAUL H. BRINK.
JAMES B. AYERS.
